United States Patent Office

Des. 209,960
Patented Jan. 23, 1968

209,960

STADIUM SEAT

Edward M. Rogers, Jr., Birmingham, Ala., assignor to
Birmingham Ornamental Iron Company, Inc., Birmingham,
Ala., a corporation of Alabama

Filed Sept. 6, 1966, Ser. No. 3,727

Term of patent 14 years

(Cl. D15—8)

Fig. 3

Fig. 4

FIG. 1 is a side elevational view of a stadium seat showing my design, the undisclosed side being a mirror image of the side shown;

FIG. 2 is a top plan view;

FIG. 3 is a front elevational view of the same; and
FIG. 4 is a rear elevational view drawn to a smaller scale.

I claim:

The ornamental design for a stadium seat, as shown and described.
